UNITED STATES PATENT OFFICE.

FRED W. BARKLEY, OF WINTHROP, MASSACHUSETTS, ASSIGNOR TO ALBERTO BARKLEY, OF PAINTED POST, NEW YORK.

OVERROTATING CHECK FOR CALCULATING MACHINES.

Original application filed March 18, 1921, Serial No. 453,356. Divided and this application filed March 18, 1921. Serial No. 453,357.

The invention relates to calculating machines of the type having a suitable selecting mechanism, and operating mechanism, a novel over rotating device for obtaining 5 a certain calculation which can be indicated on one or more rotary registering dials to obtain a definite or predetermined result. The invention consists of a mechanism for preventing the rotary dials and operating 10 mechanism from over rotating to ensure accuracy in manipulation of rapid operations and makes a positive stop or check of the rotating members at high speed. It also consists of a double acting over rotating 15 check which is extremely effective in either direction of rotation of the operative members.

The object of the invention is to provide a calculation machine having an effective 20 rotating mechanism for allowing certain numerals to be selected to obtain a definite calculation adapted to be used with a novel double acting over rotating check which can be operated in either direction of rotation 25 which is durable, practical, noiseless, and inexpensive to manufacture. A complete description of the calculating machine and my improvements are as follows, reference being made to the accompanying drawings 30 of which—

Figure 1 is a side elevation of a calculating machine with the casing in section with parts broken away to show the operating mechanism.

Figure 2 is a corner plan view of the machine showing the operating mechanism.

Figures 3, 4, 5, and 6 show the over rotating mechanism in different operating positions.

Fig. 7 is a plan view of the over rotating mechanism.

Figure 8 is a side elevation of the carrying over mechanism.

The calculating machine is provided with operating keys ranging from 0 to 9, inclusive, which are connected to, and set up the calculating mechanism. The calculating mechanism is located in a suitable casing 10, having a cover 11, and a transverse sliding carriage 12. Formed on the sliding carriage, 12, is an operating finger 13, for lifting the carriage and moving it back and forth across the machine and calculating mechanism in accordance with the calculat-

ing operations required. Also formed on 55 the carriage 12, is a catch 14 which cooperates with the holes 15 formed in the cover 11, which registers with the set of dials and mechanism required to perform a certain calculation. Mounted in the casing 11 are several sets of operating keys. Six sets are commonly used but as many sets can be used as is necessary in accordance with the size of the machine. Each set of keys indicates the numerals from 60 zero to nine inclusive, and each succeeding set will be indicated by numerals and small letters, *a*, *b*, *c*, etc. As each set of keys and operating parts are identical in construction, a description of one will be sufficient. The 65 six sets of keys will have a range of calculation from one to 999,999 and further calculations may be obtained by manipulating the carriage 12.

When the numerals are selected to be calculated the results are obtained by rotating the crank 16. To obtain a result in addition and multiplication the crank 16 is turned in one direction, and for subtraction and division the crank 16 is turned in the opposite direction. The result of the calculation is shown through the window 17, formed in the carriage 12. To clear out the figured calculation, the dials are returned to the zero position by the handle 18, which 75 controls the clear out mechanism. The numerals showing through the windows 17 indicate the numerical result determined by the keys from 1 to 9 inclusive and the operation of the crank 16 in relation to a given formula calculated. Each of the six sets of selecting keys are marked with ten numerals ranging from zero to nine, which 80 controls the rotating registering dials and each succeeding dial marking in the next order of ten in either direction. The keys, zero to nine, *a*, *b*, *c*, etc. are mounted in a housing secured to the cover 11 which allows the keys to be readily placed in position or taken out as the condition requires. The 85 keys are guided in their vertical movement by the cover 11 and plate 19, and are constantly pressed upwardly by the spring 20, that is if the keys are pressed downwardly by the operator, it operates the setting-up 90 mechanism and also locks it temporarily in position and when released the keys and setting-up mechanism will be returned to 95

the inoperated position by the spring 20.

When a key is pressed downwardly by the operator in a calculating operation it is automatically locked in position until the next key in the bank is operated. When the next succeeding key is operated it not only automatically is locked in position, but it automatically unlocks the previously operated key which returns to its inoperative position. The zero key in each bank of keys does not function only to unlock the downward pressed keys in its respective bank, but unlocks the keys which are set which allows them to return to the non-operative position. Forming a part of the key housing is a stationary plate 21 on which part of the setting-up mechanism is secured. Superimposed on the stationary plate 21 is a sliding plate 22 having ten slots 23 machined therein through which the ten keys extend for operating the setting mechanism. Formed on the keys from one to nine inclusive are cam surfaces 24, of different length which are designed to give variation in travel to the sliding plate 22, which in turn operates the setting-up mechanism. Each of the nine keys has a cam surface of sufficient dimension to move the sliding plate 22 a distance corresponding to the numeral used, that is, key 1 would move the shortest distance which moves the sliding plate sufficiently to move the setting-up mechanism a corresponding amount to bring the numeral 1 to view on the registering dial.

When the numeral 9 is used the sliding plate 22 is moved the longest distance which would cause the setting-up mechanism to be moved a corresponding amount to bring the numeral 9 to view on the registering dial. All intervening numerals, when used, would cause the setting-up mechanism to be moved correspondingly to bring the numeral to view in the registering dial.

Mounted on the stationary plate 21 are the bell cranks 25, *a*, *b*, *c*, etc., corresponding to the number of banks of keys used which are operated by the sliding plates 22, *a*, *b*, *c*, etc. The bell crank 25 is fulcrumed at 26 on the stationary plate 21.

Integral with the bell crank 25 is a projection 27, which cooperates with the sliding plate 22 for swinging the bell crank 25 into the designated position determined by the operation of any one of the keys from 1 to 9 inclusive. The swinging movement of the bell crank 25 imparts an axial movement to the gear 28, mounted on the shaft 29. The gear 28 rotates on the shaft 29 and also is free to move axially thereon within the range of the cage gear 30. This range of movement allows the selecting mechanism to operate within the range of numerals 1 to 9 inclusive. The selecting mechanism is controlled by the operating handle 16, shaft 31, which is a part of the handle 16, bevel

gears 32 and 33. Shaft 34, which is provided with suitable bearings, bevel gears 35 and 36, and shaft 37. The shaft 37 extends across the machine and is adapted to receive a plurality of disks 38, on which a part of the selecting mechanism is mounted. The part of the selecting mechanism mounted on the disks 38, consists of nine strips 39, made preferably of metal and each strip indicated by 1, 2, 3, 4, 5, 6, 7, 8 and 9 corresponding to the keys operated to obtain a certain operation. The nine strips 39 are each provided with a tooth and a clearance depression 40, each strip having a tooth and depression of different length. The strips will mesh with corresponding teeth on the gear 28 indicated by the setting-up mechanism, and clear the remaining teeth by passing through the depression. Each one of these strips will mesh with a corresponding tooth on the gear 28, and if the said gear 28 is moved axially along the shaft by the key 5, strips 1 to 5 inclusive of strips 39 will mesh with a corresponding number of teeth on the gear 28, thereby moving the distance of five teeth. If any one of the keys from 1 to 9 inclusive is operated it will move the gear 28 axially on the shaft 29 into a position corresponding to the number of strips 39 indicated. When a numeral is selected the key bearing that numeral will be pressed downwardly, thereby, moving the gear 28 axially on the shaft 29 to a position corresponding to the key selected. The operating handle is then rotated in the direction desired which causes the disks 38 and strips 39 to rotate one revolution. By this operation the strips 39 corresponding to the key depressed cause the gear 28 to rotate the distance or numeral designated. The rotating movement of the gear 28 is communicated to the registering dial 41, *a*, *b*, *c*, etc. through the cage gear 30, intermediate gear 42 and dial gear 43 thereby showing the result of the calculation on that particular dial 41.

The over-rotating check which is the main embodiment of my invention consists of a lever 49 having a wiping foot which follows the cam contour of the disc 38 and raises and lowers the lever as the condition requires.

The lever 44 is loosely mounted on the rocker shaft 45. Pivotedly secured to the opposite end of lever 44 is a pawl 47, which engages the teeth of the gear 42 and prevents it from overrotating beyond a predetermined position.

The lever and pawl are controlled by both the cam surface on the disk 38 and by the rocker shaft 45 at a predetermined time, either on a forward or reverse movement. The lever 44 is broken away at one end to show the position of the pawl 47, as indicated by the broken portion 48, Fig. 3. The

hook portion of the pawl 47 rests against the rocker shaft 45 which limits its movement in that direction. When the opposite end of the pawl engages the teeth of the gear 42 and the movement of the said gear 42 is in a counter clockwise direction the lever 44 is operated by the cam surface of the disk 38 and serves as a positive stop to prevent over-rotation.

10 In Fig. 3 the lever 44 is on an upper cam surface with the pawl 47 in a checking position between the teeth of gear 42. In this relation the lever 44 and pawl 47 can be considered as integral with each other 15 because the pawl 47, which is pivotally secured to the lever 44 is prevented from turning by the shaft 45 in one or the forward direction, as the gear 42 rotates in a counter-clockwise direction, and as the pawl 47 is prevented from turning by the shaft 45, it is obvious that a positive stop can be obtained. Fig. 4 shows lever 44 in the forward operating position having dropped down to the lower cam surface throwing the 25 pawl out of engagement with the gear 42 which is now free to rotate.

In Fig. 5, the gear 42 has rotated to a predetermined position and has just been locked by the lever 44 riding upon the upper 20 cam surface and the pawl 47 which has engaged the gear 42, preventing further rotation. This forward checking mechanism in addition to other mechanism, prevent over-rotation when the machine is operated 35 in the reverse direction, when the calculations are in subtraction and division. It is obvious as shown at Fig. 6, that lever 44 is raised away from the cam surface by the lever 50 wiping against the outer cam surface of the cam 51 causing the opposite 40 end of the lever 52 to engage the pin 53 and turn it with the shaft 45 until the said pin 53 comes in contact with the pin 54, causing it to lift the lever 44 away from the cam surface of the disk 38 and is held in this position during the entire operation. The over-rotating operation depends entirely on the pawl 47 and spring 49. When the disk 38 moves in a counter-clockwise 45 direction and the gear 42 rotates in a clockwise direction by the operating mechanism, the pawl wipes over each tooth against the tension of the spring 49 until a predetermined tooth in the gear 42 is reached. The 50 position desired is determined by the selecting mechanism or after the selecting or transfer operation is complete, after which the power is removed from the gear 42 and is immediately prevented from further rotation by the pawl 47 and spring 49. When the predetermined time is reached for the 55 gear 42 to stop, power is removed by the selecting and transfer mechanism and the spring 49 is sufficiently strong to overcome 60 the momentum of the gear 47, thereby

causing it to stop. The cam 51 holds the lever 44 in an upward position during one revolution until the lever 50 again enters the space cut in the cam and the lever 50 then drops back into the position shown 70 in Figure 3 the opposite position being shown in Figure 6.

When the calculation requires a greater numeral than nine on any one dial a carrying-over mechanism is provided to automatically carry over the result to the next dial in the order of 10. For example, in a calculation in addition, five and five is added together which necessitates the use of the key 5 and the turning of the operating 75 crank 16 twice, thereby turning the dial 41 one revolution and registering zero, and also turning the next dial which will register one, thereby making a total reading of ten.

The carrying over mechanism consists of 80 dial 41 and dial gear 43 the latter being provided with a pin 43' Figure 8, which is brought into action in addition and multiplication when the gear 43 is rotated to the last tooth, or nine-tenths of its revolution. In this position further movement of the gear 43, on which the pin 43' is located, engages the bevel end 55 of the arm 56 thereby forcing it downwardly and carrying with it the lever 57 having the projection 58 integral therewith, into the path of the cam 59 of the carrying over finger 60, which causes it to engage the intermediate gear 42 which in turn operates the dial gear 43 and dial 41 of the next higher order registering the 90 100 result.

In subtraction and division the dial gear 43 travels in the opposite direction, and the pin 43' instantly engages the opposite side 105 of the bevel surface 55 on the arm 56, forcing it downwardly for the carrying-over operation. The lever 56 is integral with the lever 57 and the two levers being connected by the cross piece 61. The downward movement of the lever 56 is communicated to the lever 57 and causes it to be released from the spring catch 62, at the same time allowing the projection 58, formed on the lever 57, to drop into the path of the carry-over 110 finger 60. The spring catch 62 is secured to the stationary collar 63 by a screw. The carrying-over finger 60 is pivotally secured to the discs 38 as shown in Figures 4, 5 and 6. The portion of the carrying-over mechanism extends through the disc 115 38 and is pivoted through the lug not shown, sufficient clearance being provided to allow the member to swing upwardly. Extending across to the next disc is an arm, forming a part of the carrying-over finger 60 which is held from sidewise movements by a slot. The upper part of the device is formed into two bevel cam surfaces 59, as mentioned hereinbefore, in the form of a letter A. Integral with this is the tooth 120 125 130

portion which engages the gear 43 of the next set, that is, when the lever 60 moves into position the bevel cam surface 59 wipes against it and causes the tooth portion to move in the path of rotation to engage the tooth of the gear 43 of the next dial gear 43. Formed in the disc 38 is an offset projection 64 which, in its path of rotation, comes into contact with the projection 58, formed on the lever 57, which forces it back into the spring catch 62 as shown in Figure 8.

All operating parts of the machine, work the same in both directions, with the exception of the over-rotating check and carrying-over mechanism, the former being the embodiment of my invention. In the reverse position a duplicate carrying-over mechanism 65 is employed. The construction and operation of the carrying-over mechanism is identical in each set and is set in a position in the disc to allow the carrying-over operation to take place at the proper time.

In the reverse operation, which is used in subtraction and division calculations, the carrying-over mechanism is located in five of the discs. In order to prevent all five of them from operating together they are set in a spiral relation on the disc and in relation to themselves, so that if one carrying-over mechanism operates at a certain time, the next one will be several degrees before or after, according to the direction of rotation.

In operation, calculations are performed in addition, subtraction, multiplication, and division. These calculations call for distinct and complete operation of the mechanism for determining the result of the calculation. A standard adding machine keyboard is used for the setting up numbers to be added, subtracted and divided and forms part of the selecting mechanism. In proper relation to the keyboard is a suitable crank 16 for performing the operation of calculation. On the back of the machine is a carriage holding the dials 41 which shows the results and proofs of the operations as they are performed. The crank 16 can operate clockwise and counterclockwise. In examples of multiplication and addition the crank is turned in one direction, and for subtraction and division the crank is turned in the opposite direction. When the zero keys are pressed downwardly, it is only for releasing the other key in the same bank which has been used. The carriage 12, having the result dials mounted therein, may be shifted to the right or to the left with ease and accuracy to obtain the results in conjunction with the selecting and operating mechanism. To obtain a result in addition or multiplication any of the keys from 1 to 9 inclusive, in as many sets of banks of

keys as desired may be pressed downwardly and held by a suitable lock until the other key is operated in the same bank of keys when it is unlocked or when it is cleared out after the calculating operation has taken place. This downward movement of the keys in their respective bank causes the sliding plate 22 to move to the right, thereby imparting a swinging movement to the bell crank lever 25. As the bell crank lever 25 swings on its pivot it causes the selecting gear 28 to move axially within the range limited by the cage gear 30. The operating crank 16 is then turned one revolution which causes the disc 38 to turn in the direction of the arrow A, Figure 1, thereby bringing one of the respective gear bars from 1 to 9 inclusive, into mesh with the selecting gear 28, and causes it to turn, recording the numeral or key previously set up. This movement of rotation of the gear 28 imparts a proportional movement of rotation to the cage gear 30, intermediate gear 42, dial gear 43 and dial 41, thereby showing the result or numeral through the window 17. When any of the strip bars from 1 to 9 inclusive are in line to engage the gear 28, the over-rotating lever 44 drops down into one of the lower cam surfaces formed on the disc 38, to cause the pawl 47 to move out of the path of rotation of the gear 42, thereby allowing the whole train of gears and dial 41 to rotate as designated. Further rotation of the disc 38 will cause the over-rotating check lever to be raised to the upper cam surface, and the gears are again locked in position until the next operation.

In subtraction and division the operating crank 16 is turned in the opposite direction. One revolution causes the discs 38 and selecting bars from 1 to 9 inclusive to rotate in the opposite direction as well as all the other rotating members thereby showing the predetermined results through the window 17 of the carriage 12. During the reverse operation, the over rotation check is again brought into action by a device embodying my invention, which causes the shaft 45 to be rotated sufficiently to cause the arms 53 to turn and engage the pin 54 on the pawl 47 lever 44 and lift it out of the path of the cam surfaces formed on the disc 38, thereby holding it rigidly in position and transferring the over-rotation friction of the pawl 47 to the spring 48 the tension of which is sufficient to prevent it from over-rotating but allows it to rotate when power is used.

When the calculating operation is carried over from one registering dial to the next in the order of ten a device is provided known as a carrying-over mechanism. When the carrying-over mechanism reaches a certain position, the tooth 9 of dial gear 43 has reached a point where the result is to be carried over to the next dial by my special car-

rying-over device. The carrying-over operation depends first on the pin 54 located on tooth 9 of the gear 43. The rotating movement of the pin 54 causes it to wipe against the bevel surface of the yoke lever 56 causing the latch on the said lever 57 to be released from the catch 62, permitting it to drop into a downward position to allow the gear to move a predetermined distance to show the designated calculation. In the reverse movement the pin 54 engages the opposite side of the bevel surface formed in the arm 56 forcing it down in the same manner as before to complete the carrying-over operation. By this movement the projection is brought into the path of the gear causing the pivot to swing outwardly into the path of the gear, thus imparting a rotating movement thereto and carrying over the result of the operation to the next dial.

In the reverse carrying-over movement the mechanism is the same except a duplicate carrying-over lever is used at a different time to perform the reverse operation.

25 In accordance with the provisions of the patent statutes I have described the principles of operation of my invention together with the apparatus I now consider to represent the best embodiment thereof, but I desire to have it understood that the apparatus shown is only an illustration and that the invention may be carried out by other means.

The subject matter disclosed, but not claimed in the present application forms the subject matter of a co-pending application, filed March 18, 1921, Serial Number 453,356.

What I claim as new and desire to receive by Letters Patent of the United States, is.

40 1. In a calculating machine, dial actuating mechanism therefor, a lever controlled by the actuating mechanism to prevent over-rotation in one direction, a spring controlled pawl on the lever and means for throwing the pawl in checking relation to the dial elements, and at the same time throwing the lever out of engagement with the actuating mechanism to prevent over-rotation in the opposite direction.

50 2. In a calculating mechanism, dial actuating mechanism an over-rotating preventer locked in position to prevent overthrow in one direction under a predetermined operation of the calculating mechanism, and resiliently held in overthrow preventing position under reverse movement of the calculating mechanism.

3. In a calculating machine, an overthrow preventer including a movable element to cooperate with the dials of the machine to prevent overthrow thereof, means for locking said element against movement in one overthrow position, and means for resiliently holding the element against movement in another overthrow position.

65 4. In a calculating machine, an overthrow preventer including a movable element to cooperate with the dials of the machine to prevent overthrow thereof, means for positively locking said element in one position to provide a fixed overthrow preventer for the dials in movement thereof in one direction, and resilient means for such element to resiliently hold said element as an overthrow preventer for the dials in movement thereof in the opposite direction.

5. An overthrow preventer for calculating machines including a lever movable to various positions during the calculating operation, and an overthrow check carried by said lever, said check being fixed against movement in one position of the lever to provide a positive overthrow lock and being resiliently held against movement in another position of the lever to provide a resiliently resisted overthrow lock.

6. An overthrow preventer for calculating machines including a lever movable to various positions during the calculating operation, a check pivotally mounted on the lever to cooperate with elements of the calculating machine to prevent overthrow thereof, means operated during movement of the calculating mechanism in one direction to lock the check with relation to the lever, and a spring between said lever and check to hold the latter independent of the lever as an overthrow preventer during movement of the calculating mechanism in the reverse direction.

95 7. An overthrow preventer for calculating machines including registering dials, a check to cooperate with said dials to prevent overthrow thereof, a lever pivotally supporting said check, a spring interposed between said lever and check, and means included in the calculating mechanism for fixing the check rigidly with the lever in movement of the dials in one direction, and means included in the calculating mechanism for freeing the check to the holding influence of the spring alone as an overthrow preventer in the reverse movement of the dials.

100 105 110 FRED W. BARKLEY.
